UNITED STATES PATENT OFFICE.

LINUS TERRY FURNAS, OF LIMA, OHIO.

DRESS-FORM.

1,158,199.

Specification of Letters Patent.

Patented Oct. 26, 1915.

Application filed March 10, 1915. Serial No. 13,407.

To all whom it may concern:

Be it known that I, LINUS TERRY FURNAS, a citizen of the United States, and a resident of Lima, in the county of Allen and 5 State of Ohio, have invented a new and Improved Dress-Form, of which the following is a full, clear, and exact description.

The invention relates to dress forms, such as shown and described in the Letters Patent 10 of the United States, No. 1,107,055, granted to me on August 11, 1914.

An object of the invention is to provide a new and improved dress form provided with Shirred ruffles for rectifying defects in 15 the human figure, and arranged to obviate slipping of the draw string or cord through the loop of the loop string, thus preventing the ruffle from drawing up hard when Shirring the same after washing and allowing ready flattening out of the ruffle 20 preparatory to washing.

A further object of the invention is to provide a dress form for each side of the garment and made in a front and rear section, of which the rear section is provided 25 with an extension at the rear to reach under the arm portion of the garment for shaping and filling out purposes.

In order to accomplish the desired result 30 use is made of Shirring and limiting means on a flounce to permit of Shirring the same, the said means comprising interengaging loop members for limiting the Shirring to form a ruffle of the length of one of the 35 loops, and a stop on the flounce in the path of the loop members to limit the Shirring movement thereof. Use is also made of dress forms at the front portions of the garment, each form consisting of Shirred 40 front and back sections, the back section having a Shirred rearward extension reaching under the corresponding armhole of the garment.

A practical embodiment of the invention 45 is represented in the accompanying drawings forming a part of this specification, in which similar characters of reference indicate corresponding parts in all the views.

Figure 1 is a perspective view of a brassière as applied and provided with the improved dress form, the brassière being in 50 closed position; Fig. 2 is a similar view of the same with the brassière opened; Fig. 3 is an enlarged cross section of the dress form 55 on the line 3—3 of Fig. 4; Fig. 4 is a face view of the same with the parts broken out

and one end of a flap turned back; Fig. 5 is a similar view of a portion of a flounce provided with a modified form of the stop for the draw string and the loop string; 60 Fig. 6 is a face view of one front portion of the brassière with the flounces in position thereon; and Fig. 7 is a similar view of the same with the flounces untied one relative to the other and one of the flounces 65 turned up.

In re-shirring ruffles after the garment is washed the user often has considerable difficulty in correctly Shirring the ruffle to provide the desired fullness, the ruffle being either Shirred too much or not enough. In Shirring the ruffle with the means shown and described in my Letters Patent above referred to, the draw string is made to slip through the loop thus causing the ruffle to 75 draw up hard when Shirring and to prevent ready flattening thereof when unshirring. In order to overcome this defect the following arrangement is made: The body A of the brassière, corset cover, or other garment, is shown open at the front and each of the front portions A' is provided at the under face with a ruffle made in front and rear sections B and B'. The upper edges of the sections B and B' are provided with 80 hems C and C' engaging a string D secured at its ends to the corresponding front A' near the upper end thereof, as will be readily understood by reference to the drawings. The front section B is provided at its front 85 edge with a tying string E adapted to be tied to a similar string E' attached to the front A' of the garment. The back section B' is provided with an extension B² extending along the armhole of the garment 90 approximately at the bottom thereof, and the rear edge of the extension B² is provided with a tying string E² adapted to be tied to a corresponding string E³ on the garment at the bottom of the armhole. By 95 providing the rear section B' with this armhole extension it is evident that a desired shape and fullness can be given to the garment at this particular point. The same construction also applies to back-opening 100 garments.

The foundation F of each section B, B' is provided with a number of flaps G secured at their upper ends to the foundation piece F. A hem H is formed by each flap G in 110 conjunction with the foundation F, and within each hem H are arranged a loop

string I and a draw string J. The loop string I is doubled up to form a loop and its ends are secured by stitches I' or other means to the corresponding end H' of the hem H. The doubled-up loop string I is of a length corresponding approximately to the length of the flounce after being shirred. The draw string J is also doubled up and passes through the loop of the loop string I, 10 the ends of the draw string J extending through the other open end H² of the hem H and their terminals are tied or otherwise fastened together as indicated at J'. A stop K is arranged at the end H² of the hem H to 15 limit the shirring movement of the loop string I and the draw string J by causing the loop of the loop string I to abut against the stop K at the time the draw string J is drawn outward and the flap G is shirred to 20 form the flounce. The stop K is preferably in the form of a piece of tape extending across the end of the hem H and being secured at its ends to the foundation F. The tape provides two separate passages for the 25 ends of the draw string J and consequently the draw string cannot entirely be pulled out of the hem H.

Instead of using a tape for providing the 30 separate passages for the ends of the draw string J, a stop K' may be made by a tack or row of stitches extending longitudinally approximately at the middle of the hem and the foundation F, as shown in Fig. 5.

When the flounce is flattened out and it is 35 desired to shirr the flounce, it is only necessary for the user to pull the free outer end of each draw string J so as to shirr the ruffle along the loop string I, it being understood that on pulling on the free end of the draw 40 string J the loop string I is drawn through the hem H toward the end H², and when the stop K is reached the ruffle is shirred on the loop string I. From the foregoing it will be 45 seen that the length of the shirred ruffle corresponds to the length of the loop string I, which is the required length to shirr the ruffle to the proper fullness. The draw

strings J of the adjacent flounce sections B and B' are tied into bows so as to connect the adjacent edges of the sections with each other and at the same time hold the flounces in shirred position. 50

From the foregoing it will be seen that the user of the garment after washing the same can quickly and correctly shirr each ruffle to 55 obtain the desired fullness and without danger of shirring the ruffles too much or not sufficiently and without danger of the shirring strings slipping through the open ends of the hems. 60

Having thus described my invention, I claim as new and desire to secure by Letters Patent:

1. A dress provided with a flounce having a hem, a loop string within the said hem and doubled up to form a loop, the ends of the loop string being secured to one end of the flounce, and a draw string extending within the said hem and doubled up, the draw string passing through the loop of the 65 loop string and having its ends extending through the other end of the hem, the draw string ends passing through separate 70 passages at the last-mentioned end of the hem.

2. A dress form provided with a flounce 75 having a hem, a loop string within the said hem and doubled up to form a loop, the ends of the loop string being secured to one end of the flounce, a draw string extending within the said hem and doubled up, the draw 80 string passing through the loop of the loop string and having its ends extending through the other end of the hem, and a tape attached at its ends to the flounces and extending across the last-mentioned end of the 85 hem to form separate passages for the ends of the draw string.

In testimony whereof I have signed my name to this specification in the presence of two subscribing witnesses.

LINUS TERRY FURNAS.
